UNITED STATES PATENT OFFICE.

PER MOLIN, OF ESLÖF, SWEDEN.

FOUNTAIN-PEN.

SPECIFICATION forming part of Letters Patent No. 769,393, dated September 6, 1904.

Application filed March 4, 1903. Serial No. 146,137. No model.

To all whom it may concern:

Be it known that I, PER MOLIN, cork manufacturer, a subject of the King of Sweden and Norway, and a resident of Eslöf, in the Kingdom of Sweden, have invented certain new and useful Improvements in Fountain-Pens, of which the following is a specification, reference being had therein to the accompanying drawings.

- 10 This invention relates to improvements in fountain-pens or such penholders in which the pen is supplied with ink from a reservoir mounted in the barrel and made of rubber or any other suitable elastic material.
- 15 The object of my invention is to provide means for compressing the said reservoir from the outside of the penholder, so that the reservoir when permitted to expand can be filled with ink or other liquid sucked in through the 20 nozzle of the reservoir.

In the accompanying drawings, Figure 1 is a longitudinal sectional view of a fountain-pen arranged in accordance with this invention. Fig. 2 is a cross-section on the line 2-2 of Fig. 1. Fig. 3 is a longitudinal sectional view of a modified form of the invention.

b is the pen, fixed in the barrel *a* in the usual manner.

c is the reservoir, of rubber or other suitable elastic material and mounted in the barrel *a*. The front end of the said reservoir is open and incloses tightly the inner end of a tube or nozzle *d*, fixed in the front end of the barrel *a* and projecting from the same near to the point of the pen. In the side of the nozzle *d* adjacent to the pen *b* one or more holes *k* are provided, through which ink can freely percolate from the reservoir to the pen in proper quantities when writing is going on.

40 According to this invention a springy tongue-piece *e* is mounted in the barrel longitudinally to the reservoir, said tongue being preferably fixed in the front end of the barrel between the same and the wall of the reservoir. In the rear end of barrel *a* a movable pressing-button *f* is mounted. A tongue-piece *g*, projecting into the barrel, is fixed to the said button *f*, and consequently can be pushed along the barrel by means of the said

button *f*. Near the free rear end the tongue 50 *g* is bevel outward into the shape of a semi-circle or other suitable curve or provided with a convex bearing-piece. Also the free front end of the tongue *g* has a similar curved part or bearing-piece, but bent into opposite direction—viz., inward—as shown in the drawings.

The reservoir *c* in the barrel is charged with ink or other suitable liquid by pressing the button *f* inward, the tongue *g* being then advanced, so that its inwardly-curved part is 60 pushed over the tongue *e* and its outwardly-curved part. Thus the tongue *e* will be pressed toward the reservoir *c* and compress the same. After the air has been ejected from the reservoir in the said manner the point of the nozzle *d* is dipped into ink or liquid. When the button *f* is released, it will be returned, together with the tongue *g*, by the pressure 65 from the tongue *e* upon the inclined inner end of the tongue *g*, and the reservoir *c* is thus 70 permitted to expand, ink or liquid being then sucked into the reservoir through the hole of the nozzle *d*.

In order to insure the return stroke of the button *f* and the tongue *g* to the normal position, the button may be acted upon by a spring, as shown in Fig. 3, in which a helical spring *h* is mounted between the inner end 75 of the button and a stationary wall *i* in the barrel.

By means of the button *f* and the said tongues *e* and *g* the reservoir *c* can be compressed to its whole or substantially whole extent, and thus be filled with ink or liquid after each depression and releasing of the button *f*.

Having now described my invention, what I claim as new, and desire to secure by Letters Patent, is—

1. In a fountain-pen, in combination, a 90 barrel, an ink-reservoir of elastic material therein, a reservoir-compressing strip held by one end within the barrel and alongside the reservoir the other end being free to move sidewise, a push-button, a tongue carried by 95 the push-button and adapted when reciprocated to engage and actuate the said strip to compress the reservoir, and a spring nor-

mally holding said push - button projected and out of operative connection with the said compressing-strip.

2. A fountain-pen comprising a barrel, a compressible ink-reservoir therein, a spring reservoir-compressing strip secured by its forward end within the barrel and alongside the reservoir, a push-button in the rear end of the barrel, a spring holding said button normally withdrawn, and an inclined member carried by the button and adapted to engage the rear end of the reservoir-compressing member.

3. In a fountain-pen in combination, a barrel, a tubular nozzle for one end thereof and provided with a feeding-opening at one side and beneath the pen, a pen, an elastic reservoir within the barrel and communicating with said plug, a push-button at the rear of

said reservoir, a compressing member lying 20 alongside said reservoir, means for actuating said compressing member from the push-button and means for normally holding said push-button out of action.

4. In a fountain-pen, in combination, a barrel, 25 a compressible ink-reservoir within the barrel, a spring compression-bar secured by one end alongside of and near one end of said ink-reservoir, and a movable plunger or push-button adapted to engage said compression-bar to compress the ink-reservoir.

In witness whereof I have hereunto signed my name in the presence of two subscribing witnesses.

PER MOLIN.
